METHOD OF HYDROLYZING PROTEIN MATERIALS

Frederick C. Bersworth, Verona, N. J., assignor to
 The Martin Dennis Company, Newark, N. J., a
 corporation of New Jersey

No Drawing. Application October 24, 1940,
 Serial No. 362,613

4 Claims. (Cl. 260—529)

This invention relates to chemistry and more particularly to organic chemistry and has for its object the provision of an improved method of hydrolyzing organic compounds. Another object is to provide an improved method of hydrolyzing proteins to amino acids. Still another object is to provide means to maintain a substantially constant oxidation-reduction potential during hydrolysis reactions. Other objects and advantages will be apparent as the invention is more fully hereinafter disclosed.

In accordance with these objects, I have discovered that in many hydrolysis reactions the organic material being subjected to hydrolysis, the hydrolyzed product and the intermediate products formed during hydrolysis are each sensitive to oxidation and reduction, and that oxidation and reduction reactions on these said products markedly interfere with the progress of the hydrolysis reaction and the ultimate kind, quantity and quality of the yield obtained and that the oxidation and/or reduction products produced seriously interfere with the purification and isolation of the ultimate hydrolyzed product.

I have found that by conducting or carrying out the hydrolysis reaction at a substantially constant or fixed oxidation-reduction potential the difficulties heretofore experienced in obtaining satisfactory hydrolysis of organic compounds are substantially eliminated.

As one specific embodiment of the present invention but not as a limitation of the same, the adaptation of the present invention to the hydrolysis of protein to amino acid will be described. Heretofore in the art, it has been proposed to hydrolyze protein into amino acid by digesting the protein with caustic alkali solution at elevated temperature. Under these conditions it is commonly accepted that water is added to the

5 Each of these materials when subjected to hydrolysis are converted at least in part into amino acids. The yield of such acid and the specific kind and quality of acid obtained however varies widely even as between successive batches of material from the same source hydrolyzed substantially identically. By the practice of the present invention, however, substantially reproducible results may be obtained in hydrolyzing successive batches of the same material and the hydrolysis reaction itself becomes adapted to practice on a continuous or successive large scale batch production basis with relatively high percentage yields of amino acids of consistent composition, thereby greatly simplifying subsequent purification and isolation of the acids from the hydrolysis residues and from each other.

10 I have found that by introducing readily oxidizable and reducible material in the reaction mixture of protein and caustic alkali a substantially constant or fixed oxidation-reduction potential characteristic of the oxidizable-reducible mixture may be obtained in the reacting protein-caustic alkali mixture which potential, per se, may vary widely without essential departure from the present invention. I have found that in the presence of such a substantially constant or fixed oxidation potential the hydrolysis reaction proceeds normally as a time-temperature reaction 15 at a rate which is determined by the temperatures and pressure and that the yield of amino acid obtained or conversely the losses incident to oxidation and reduction side reactions is stabilized and is directly effected by the specific oxidation-reduction potential established by the oxidizable-reducible mixture employed although within fairly wide ranges of potential the amino acid yields are consistently higher than those heretofore obtained in the absence of such oxidizable-reducible mixture employed in the practice of the present invention.

20 In order to maintain a substantially constant or fixed oxidation-reduction potential in the hydrolyzing protein-caustic alkali reaction mixture, means must be provided to absorb or to take up the free and/or ionized oxygen and the free and/or ionized hydrogen generated in the reaction mixture. This result may be obtained in a plurality of ways such as by the use of a multi-valent inorganic compound, such as for example the well known multi-valent vanadium and manganese salts, by the use of an organic compound that is more sensitive to oxidation and reduction than the protein, amino acid or intermediate hydrolyzed products present, such as for

25 linkage of the protein resulting in the formation of $—\text{COOH}$ and $\text{H}_2\text{N}—\text{C}—$ compounds. However, protein is a naturally occurring organic compound and while recognized generally as being an anhydride of amino acid it is known to be associated with other organic and inorganic compounds that interfere with the conversion of the protein by hydrolysis into amino acids and the recovery of the acids from the resultant hydrolyzed mixture. Examples of materials commonly known to be protein materials are the group of materials identified as soy bean meal, sugar beet residues, albumin, casein and the like.

example quinhydrone, or by the use of a mixture of oxidizable metal and hydrogen reducible metal compounds.

The latter way is preferred and as a specific embodiment of the same the adaptation of the present invention to the hydrolysis of protein by caustic alkali in the presence of a mixture of metallic lead and lead oxide (or alkali plumbate) will be described.

The usual practice in hydrolyzing protein with caustic alkali at elevated temperatures is to mix the protein with the caustic alkali solution, using a considerable excess of alkali and heating the same to an elevated temperature within the range 140-200° C. for a prolonged time interval effective to complete the hydrolysis reaction.

I have found that by introducing an oxidation-reduction potential stabilizer material or agent comprised of a mixture of lead and lead oxide into the reaction mixture, the oxidation-reduction potential in the reaction mixture is stabilized or maintained at a value which results in relatively low losses incident to oxidation and/or reduction side-reactions involving the protein, amino acids and intermediate hydrolysis products and that in addition substantially all sulfur compounds normally contaminating the protein are either eliminated from the reacting mixture or are fixed in new organic combination non-deleterious to the future use to which the amino acids normally are to be applied. As a further advantage, I have found that contrary to prior art experience the hydrolysis reaction may be carried out under pressure ranging from 100 lbs. per sq. inch up to 400 lbs. per square inch depending upon the temperature employed or the gaseous intermediate products produced and heretofore lost, thereby to increase the yield of amino acids produced and the consistency of composition of said acids from any given protein material.

The amount of the mixture of lead and lead oxide added to any given hydrolyzing mixture of protein and caustic alkali may be varied widely without essential departure from the present invention. The minimum amount appears to be that amount required to absorb the free or ionized oxygen and hydrogen with sufficient rapidity to prevent the formation of deleterious amounts of side reactions products. This factor obviously varies widely depending upon temperature, pressure, protein and relative quantities. As one example of its use, the following may be given of a typical reaction mixture:

	Grams
Protein (for example soy bean meal)	100
Caustic alkali solution (50%)	160
A mixture of finely divided lead and lead oxide in approximately equal proportions	5 to 15

Sufficient water to make a total volume of 1,000 cubic centimeters (one liter) is added before heating the same to within the range of temperatures 140-200° C. in an autoclave or similar container sealed from the atmosphere.

In general in such a reaction mixture it will be found that the initial pressure developed on heating will gradually fall as the hydrolysis reaction progresses to a stationary pressure which on cooling to atmospheric temperatures will be a minus pressure of from 10 to 16 inches of mercury. In the absence of the lead and lead oxide such a result is not obtained.

Whereas, in the above specific example, I have

disclosed a mixture of lead and lead oxide in approximately equal proportions, it is believed apparent that these proportions may be varied widely without essential departure from the present invention. It appears necessary only to provide in the reaction mixture a sufficient amount of each constituent to insure the presence of metal and oxide through the entire hydrolyzing reaction.

10 In place of metallic lead other readily oxidizable metals may be employed, such as copper, nickel, selenium, tellurium and molybdenum. The oxidation potential obtained, however, by the use of these metals will vary somewhat from that of lead leading to variations in the amount of losses, as one skilled in the art will perceive.

15 In place of lead oxide or alkali plumbate other hydrogen reducible metallic oxide and/or alkali soluble and hydrogen reducible compounds may be employed, such as copper, vanadium or molybdenum oxide or alkali vanadates and alkali molybdates, with resultant variation in the reduction potential established in the reaction mixture.

20 With most protein materials hydrolyzed as hereinabove described, however, I have found that the lead-lead oxide mixture results in the lowest losses incident to oxidation and reduction side reactions and for that reason it is preferred as a stabilizer agent in the practice of the present invention. Following hydrolysis in accordance with the present invention any lead in solution may be precipitated by subjecting the clear alkaline filtrate to treatment with hydrogen at elevated temperatures. Following such treatment the amino acids may be recovered from the alkaline filtrate in any convenient manner heretofore known in the art.

25 It is believed apparent from the above description and specific embodiment given that the present invention may be widely varied without essential departure therefrom and all such modifications and adaptations thereof are contemplated as may fall within the scope of the following claims.

30 45 What I claim is:

1. In the hydrolysis of amino acid anhydrides to amino acids by digesting the said anhydrides in an aqueous caustic alkali solution, the improvement which comprises incorporating within the solution a quantity of an oxidation-reduction potential stabilizer agent consisting of a mixture of lead and lead oxide, the amount thereof being at least sufficient to maintain a substantially constant low oxidation-reduction potential 50 in the said solution throughout the progress of the said hydrolysis reaction.

55 2. The method of hydrolyzing the amino acid anhydride content of naturally occurring organic compounds known as proteins which comprises suspending the protein in a caustic alkali solution, incorporating therein a proportion of an oxidation-reduction stabilizer agent consisting of a mixture of lead and lead oxide in total amount at least sufficient to maintain a substantially constant low oxidation-reduction potential 60 in the solution during the progress of the hydrolysis reaction, enclosing the suspension from the atmosphere and heating the said suspension to a temperature within the range 140-200° C. for an extended time interval under pressures ranging from 100 to 400 pounds per square inch.

65 3. The method of converting the amino acid anhydride content of naturally occurring proteins to amino acids which comprises hydrolyzing the said protein in an aqueous solution of a

caustic alkali in the presence of an oxidation-reduction stabilizer agent consisting of a mixture of lead and lead oxide, the hydrolysis reaction being conducted in a container sealed from the atmosphere at a temperature within the range 140-200° C. and under the steam pressure generated in the container at the temperature of heating.

4. In the hydrolysis of proteins by the method comprising suspending the protein in a caustic alkali solution and heating the solution to elevated temperatures, the improvement which

comprises enclosing the suspension from the atmosphere, heating the suspension to a temperature within the range 140 to 200° C. under the steam pressure generated at the temperature of heating and maintaining during the entire period of said heating a substantially constant low oxidation-reduction potential in said solution thereby substantially eliminating losses of the amino acid hydrolysis product as a result of the formation of oxidation and reduction side reaction products.

FREDERICK C. BERSWORTH.
